UNITED STATES PATENT OFFICE

106,147

DESIGN FOR FOLDING OXFORD EYE-GLASSES

Jacob J. Pomeranz, Brooklyn, N. Y., assignor to
T. & P. Optical Mfg. Co. Inc., New York, N. Y.,
a corporation of New York

Application July 16, 1937, Serial No. 70,479

Term of patent 14 years

To all whom it may concern:

Be it known that I, Jacob J. Pomeranz, a citizen of the United States, residing in Brooklyn, in the county of Kings and State of New York, have invented a new, original, and ornamental Design for Folding Oxford Eyeglasses, of which the following is a specification, reference being had to the accompanying drawing, forming part thereof.

In the drawing:

Figure 1 is a front elevation of folding oxford eyeglasses showing my new design, and
Figure 2 is a top plan view thereof.

I claim:

The ornamental design for folding oxford eye-glasses, as shown.

JACOB J. POMERANZ.
